UNITED STATES PATENT OFFICE

WILHELM HEINEMANN, OF ST. GEORGEN, GERMANY

LATHE HAVING FRONT AND REAR TOOL SLIDES

Application filed November 15, 1927, Serial No. 233,458, and in Germany June 21, 1926.

In the case of machine tools, more particularly lathes, having tool slides or carriers for longitudinal turning and for facing separately driven, the control of the drive is still usually done by hand, at least for some of the operations, and careful attention is required on the part of the workman to prevent damage due to starting some operation at the wrong time.

10 My invention provides means for the automatic control of the traversing mechanism in such lathes, allowing also of alternative control by hand, with an arrangement of control levers whereby when the same are moved in one direction only one drive can be effective, and when they are moved in the other direction only another drive can become effective, and I arrange also that with the control lever in a central position the support can be moved by hand.

To save time in returning the supports, and allow of quick movement in both directions, a quick drive is provided, put into operation by moving the control lever in one direction, with a manually or automatically actuated device which has been operated for the purpose, as by means of a lever actuated by an adjustable cam, which is driven by the main shaft, the lever having a gap, which allows the control lever to be moved into neutral position by a spring or gravity.

With the improved mechanism all movements of either or both supports can take effect without mutual interference, and the quick drive can be put into operation automatically or manually. The forward movements of the two supports can be proportioned to the dimensions of the work so that the two supports can finish together.

40 An example of apparatus according to the invention is shown in the annexed drawings, in which

Fig. 1 is a longitudinal section on the line A—A of Fig. 3,

45 Fig. 2 being a section on the line B—B of Fig. 1,

Fig. 3 a front view of the headstock,

Fig. 4 a front view of part of the mechanism to a larger scale, and

50 Fig. 5 a sectional view on this part.

The shaft 1 drives, by means of toothed gear or a chain, a spur gear 2 having worms 3 and 3¹, which drive shafts 4 and 4¹ by means of worm wheels 5 and 5¹. The shafts 4 and 4¹, with all the parts thereon, are alike, the shaft 4¹ serving to actuate the rear plane tool carrier, and the shaft 4 serving to actuate the forward tool carrier. A gear wheel 6 on the shaft 4 drives a gear wheel 7 and a shaft 8, connected by gears 9 and 10 to a shaft 11. On the latter is a pinion 12 meshing with the rack 13 of the sliding carrier 14. The shaft 4¹, by means of gears 6¹ and 7¹, drives a shaft 8¹ which by means of bevel gears 15 and 16 drives a shaft 17 and a shaft 18 perpendicular thereto. A pinion 19 on the shaft 18 actuates the facing tool carrier.

Assuming for example that the longitudinal slide is to advance, a hollow shaft 25 surrounding the shaft 4 is axially moved so that a nut 26 on it pushes a clutch 21 into engagement with the continuously rotating worm wheel 5. The shaft 25 is moved axially by means of a lever 22, which is, when rotated, moved axially by a screw threaded sleeve 23 fixed to it, and then shifts the shaft 25 by means of a ball bearing 24.

Fig. 4 shows the lever 22 in position for the longitudinal traverse, with a square nose 28 bearing on a pivoted pin 29, which can be rotated by a lever 61. On rotation of this pin as indicated by the arrow a recess therein releases the nose 28 and lever 22, and the lever is rocked to the right by a spring 30 or weight 30¹ screwing the sleeve 23 rearward and uncoupling the worm wheel 5 from the shaft 4. The desired action may be obtained either by means of a spring or by suspending a weight, as best shown in Fig. 3, wherein when the right disconnecting lever 22 is employed, the action is occasioned by spring 30, while when the left disconnecting lever 22¹ is employed the action is through the weight 30¹.

Automatic release by the pin 29 can be effected by the movement of a tappet 32, adjustable on a rotating disc 31 driven by a gear wheel 37 and the shaft 11. A disc 31¹ for the facing tool traverse is driven by gear wheels 34, 35, 36 and the shaft 8¹. When the tappet 32 strikes a nose 33 on the pin 32 the

pin releases the lever 22. The maximum movement of the slide has a period slightly less than that of a complete revolution of the disc 31.

5 If one or both slides are to be returned quickly to their starting positions or are to move quickly in both directions, the lever 22 is rocked to the right. The driving pulley 38 drives a shaft 39 connected by bevel gear 10 drive 40, 41, 42, 43 (the element 43 being a clutch-coupling), to the hollow shaft 44, the drive being put into engagement by a lever 59 (Fig. 2) and rod 60. A wheel 45 on the shaft 44 then drives wheels 46, 46¹ which are 15 rotatable on long sleeves 25, 25¹ splined to the shafts 4, 4¹. I will describe the action as it occurs when only the longitudinal slide is to make a quick movement.

The lever 22 being rocked to the right, the 20 sleeve 23 and ball bearing 47 act on the nut 48, and a nut 49 pushes a friction disc 50 against the wheel 46, which is thus pressed against a friction disc 51, with the ball ring 52 bearing against a flange 53. The shaft 4 25 being keyed to the sleeve 25 the fast drive is transmitted to the rack 13. The lever 22 is moved in the direction indicated by the arrow *b* by hand, or automatically by the spring 30, for which the weight 30¹ may be 30 substituted. For the latter purpose there is a pawl 54, which can rotate through approximately 360° facing a nose 55 on a spring actuated ring 56. The purpose of the ring 56 is, by means of the spring acting thereon and 35 the lug 55 mounted thereon, to prevent the lever, when pawl 54 is engaged as shown on Fig. 4 from automatically rotating in the direction of arrow *b* when for any reason it is not desired to produce the automatic 40 emergency of the slides after terminated advance. Therefore, in such instances if the pawl 54 is engaged as shown by the position of the right lever 22 of Fig. 3 the collar 56 exerts no influence. The spring 30 or weight 45 30¹ is out of action when the pawl is in the left-hand position shown, but when the pawl is rocked through 180° the spring pulls the lever 22 over to the right as soon as the traverse is to start, or a weight 30¹ operates for 50 the same purpose by means of a cord, as shown in connection with the lever 22¹. The proper position of the ring 56 is secured by the second nose 57. The purpose of the pawl 54 is as follows:—As shown in Fig. 4, it is 55 engaged in this position, the ring 56, which is subject to spring action prevents the lever 22 from being moved by its spring or prevents the weight acting thereon from moving in the direction of the arrow *b* whereby emergency 60 reverse takes place through the action of wheels 46 (see Fig. 1). If it is desired to use the pawl in this position on emergency travel (see Fig. 4), the lever must be moved by hand in the direction of the arrow *b* and the spring 65 power of ring 56 thus overcome. When the

pawl 54 is swung out approximately 360° according to the position at the right lever 22, as shown on Fig. 3, the spring 30 or weight 30¹, acting on lever 22 exerts a pull and moves lever 22 freely in the direction of the arrow *b* 70 on Fig. 4, when the advance mechanism is released through rotation of the shaft 29. The friction coupling discs 50 and 51 (Fig. 1) press against the constantly rotating thrust gear 46 and emergency operation takes place 75 and brings the slide into the initial position.

To uncouple the quick-traverse gear the lever 22 is moved by hand to the central, or this is done automatically by a tappet 58 on the disc 31, this tappet striking a nose on the 80 lever.

As will be seen, the normal traverse and quick traversing gears can never be coupled together. If by oversight the tappet 32 has not been adjusted the longitudinal slide is 85 automatically stopped in its extreme left hand position by striking the lever 61 connected to the pin 29 and rocking it in the direction indicated by the arrow *c*.

If the control is to be effected by hand when the lever 22 is in its central position, hand wheels 62, 62¹ on the shafts 4 and 4¹ are rotated for the purpose; cranks may be substituted for these wheels. The traverse of the slides can be regulated as required by means 90 of the change wheels 6, 7 and 6¹, 7¹.

What I claim is:

1. In a lathe having front and rear tool slides, the combination with each of two continuously driven auxiliary shafts for moving the slides, one for transverse feed, and one for quick return of a control lever, a screw threaded sleeve on said control lever, a main shaft, a worm wheel driven by said main shaft, a clutch actuated by the said sleeve 100 when the control lever is rocked in one direction to couple the worm wheel to the main shaft for actuating the respective slide in its traversing feed, a friction clutch for driving the auxiliary shaft for quick return of the corresponding slide, a gear wheel mounted on the said auxiliary shaft and engaging with said friction clutch, and reversing gear driving the said gear wheel, movement of the control lever in the other direction causing the threaded sleeve to uncouple the worm wheel and to couple the friction clutch to the gear wheel for the quick return, the control lever 110 when in its central position leaving the gears free for manual operation of the slide by 115 means of the same gears.

2. A lathe apparatus as in claim 1, comprising a disc rotating with the auxiliary shaft, adjustable tappets on the said disc for automatically effecting the disengagement of the traversing and quick return clutches, a lever actuated by the tappet for the traversing movement, and also actuated by hand, a pin having a recess therein and adapted to be moved by said last mentioned lever for 120 125 130

releasing the control lever by means of the recess, and means for moving the control lever after its release into its central position, thus releasing the corresponding clutch,
5 the tappet for the quick return movement moving the lever back to the central position from its position where it causes the actuation of the quick return drive, the auxiliary shaft being stopped by the disengagement of the
10 quick return clutch.

In testimony whereof I have signed my name to this specification.

WILHELM HEINEMANN.
